UNITED STATES PATENT OFFICE.

ISAAC BLUM, OF BALTIMORE, MARYLAND.

DESIGN FOR A CLASP FOR TROUSERS.

SPECIFICATION forming part of Design No. 19,052, dated July 1, 1890.
Application filed May 2, 1890. Serial No. 350,356. Term of patent 14 years.

To all whom it may concern:

Be it known that I, ISAAC BLUM, a citizen of the United States, and a resident of the city of Baltimore, in the State of Maryland, have invented a new and original Design for Trousers-Clasps, of which the following is a specification, reference being had to the accompanying drawing, forming part thereof, in which the figure is a representation of the clasp showing my design.

The leading features of my design is a trouser-clasp consisting of a section A, having its periphery, as shown, practically in the form of an elongated triangle, the longer sides

a a of which are invertedly curved, and an additional section B, extending therefrom, the outer line of which is a continuous curve or arch, as shown at *b*. Within the plate of which the clasp is composed is an ovoidal opening O.

What I claim is—

The design for trouser-clasps, as herein described and illustrated in the drawing.

ISAAC BLUM.
